UNITED STATES PATENT OFFICE.

FREDERIC M. GRANT, OF CHICAGO, ILLINOIS, ASSIGNOR TO GEAN COWGILL COMER-FORD, OF CHICAGO, ILLINOIS.

DESIGN FOR AN EMBLEM.

40,383.

Specification for Design.

Patented Dec. 7, 1909.

Application filed July 14, 1909. Serial No. 507,663. Term of patent 14 years.

To all whom it may concern:

Be it known that I, FREDERIC M. GRANT, a citizen of the United States, residing at Chicago, in the county of Cook and State of Illinois, have invented a new, original, and ornamental Design for an Emblem, of which the following is a specification, reference being had to the accompanying drawing, forming part thereof.

The figure is a face view of an emblem showing my new design.

I claim:

The ornamental design for an emblem, as shown.

FREDERIC M. GRANT.
